(57) CLAIM

The ornamental design for a hand cleaning apparatus, as shown and described.

DESCRIPTION

FIG. 1 is a right front upper perspective view showing the front, right side and top of a hand cleaning apparatus of my new design;

FIG. 2 is a right rear upper perspective view of the design of FIG. 1;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The portion of the drawings depicted in dotted lines form no part of the claimed design.
